[57] **CLAIM**

The ornamental design for a display panel for timepiece, as shown.

DESCRIPTION

FIG. 1 is a front elevational view of a display panel for timepiece showing our new design in an inactive mode; FIG. 2 is a top plan view thereof, the bottom plan being identical thereto;

FIG. 3 is a typical side elevational view thereof;

FIG. 4 is a rear elevational view thereof;

FIG. 5 is a view similar to FIG. 1 showing a normal time display indicating the sixth day, Monday and 10:00 o'clock eight minutes and 42 seconds in the morning;

FIG. 6 is a view similar to FIG. 5 in the timer mode in which the time period displayed is five minutes 24 seconds;

FIG. 7 is a view similar to FIG. 5 in the alarm set mode in which the alarm is set to activate at 9:00 o'clock in the evening.

FIG. 8 is a view similar to FIG. 5 in the dual time mode wherein 4:00 o'clock eight minutes 42 seconds in the morning is on analog type display; and

FIG. 9 is a view similar to FIG. 5 in the stopwatch mode.
